UNITED STATES PATENT OFFICE

JULIAN P. FARNAM, OF MINNEAPOLIS, MINNESOTA, ASSIGNOR TO PAGE & HILL CO., OF MINNEAPOLIS, MINNESOTA, A CORPORATION OF MINNESOTA

DESIGN FOR A LIGHT POST

Application filed September 8, 1932. Serial No. 44,771. Term of patent 3½ years.

To all whom it may concern:

Be it known that I, JULIAN P. FARNAM, a citizen of the United States, residing at Minneapolis, in the county of Hennepin and State of Minnesota, have invented a new, original, and ornamental Design for a Light Post, of which the following is a specification, reference being had to the accompanying drawing, forming part thereof.

Figure 1 is a front elevation of the light post, showing my new design, with a portion thereof broken away;

Figure 2 is a plan view of the light post; Figure 3 is a horizontal section taken on the line 3—3 of Figure 1; and Figure 4 is a vertical section taken on the line 4—4 of Figure 1.

I claim:

The ornamental design for a light post, as shown.

JULIAN P. FARNAM,
